Specification of Letters Patent. Patented May 25, 1915.

Original application filed September 28, 1911, Serial No. 651,813. Divided and this application filed October 16, 1912. Serial No. 726,126.

To all whom it may concern:

Be it known that we, FRANK B. WILDMAN and GEORGE LAWSON BALLARD, the latter a subject of the King of Great Britain and the former a citizen of the United States, both residing at Norristown, Pennsylvania, have invented certain new and useful Improvements in Knitting-Machines, of which the following is a specification.

10 Our invention relates to circular knitting machines of the type in which a main thread feed and an additional thread feed are employed, the present invention being a division of that disclosed in application for Letters Patent of the United States, filed by us September 28, 1911, Serial No. 651,813.

One of the objects of our present invention is to provide means for automatically adjusting one of the needle cams simultaneously with the introduction or removal of the additional thread.

Some of the mechanical features and connections disclosed herein are like those shown in an application for Letters Patent of the United States #623,261, April 25, 1911, and in certain Letters Patent herein-mentioned.

In the accompanying drawings, Figure 1 is a plan view of a knitting machine of the Wildman type embodying our invention; Fig. 2 is a side view of a knitting head with the feed mechanism for the additional thread used in the formation of the two-thread walled welt; Fig. 3 is a view of the cam cylinder of the cylinder needles developed and looking at the inside of the same; Fig. 4 is a front view of the feeding, cutting and clamping mechanism for the additional thread; Fig. 5 is a view of the cutting and clamping mechanism for the thread looking from the left of Fig. 4; Fig. 6 is a bottom plan view of the cutting and clamping devices; Fig. 7 is a detail view of one of the cylinder cam posts; Figs. 8 and 9 are respectively, diagrammatic face and sectional views showing the succession of changes in the fabric.

The main thread is fed to the needles by a guide 1 of usual construction, and the additional thread to form the outer wall of the tubular welt is fed through a guide 2 diametrically opposite the main guide and

consisting of an arm pivoted at 3 to a bracket 4, said arm being operated to and from the needles to present the thread thereto or remove it therefrom by means similar in some respects to that disclosed in Letters Patent of the United States granted to J. B. Hipwell, #815,167, March 13, 1906, and consisting generally of a star wheel 5 which, when operated by contact with a device on the frame, operates through gearing 6 and a cam shaft 7 to raise the lever or thread guide arm or to allow it to fall under the action of a suitable spring. At 9 is shown a cutting device for the additional thread, which is operated to sever it when the guide arm is raised, and at 10 is a clamp for holding the severed end of the thread so that when the guide arm is again lowered the thread will be presented to the needles, the clamp insuring proper control of the thread until the needles have taken it. The mechanism for operating the cutter and clamp will be referred to briefly hereinafter.

The star wheel 5 of the additional thread feeder is operated by contact with a pin 11 carried by a plate 12 which is adjusted vertically into and out of line with the star wheel by suitable pattern mechanism, (not shown).

One movement of the star wheel will throw the guide arm 2 up and the next action of the star wheel will permit the guide arm to fall to present the thread to the cylinder needles.

The cams of the dial comprise a stitch cam 12 and an advancing cam 13, and this latter may be of the form known as a wing cam, or a cam may be used such as is disclosed in Letters Patent of the United States granted to F. B. Wildman, #800,192, September 26, 1906, and carried by a two-part dial cap. Such a pivoted cam is illustrated at 18 pivoted at 14, and adjusted by a pin and slot connection at 15, when the lower cam carrying section 16 of the dial cap is moved circumferentially.

For throwing the cam carrying section, we employ mechanism similar to that disclosed in said patent consisting of a link 17 and arm 18 on a vertical shaft mounted in the cam cylinder and in turn operated by an arm 19 fixed to said shaft and by a second arm 20 on a shaft 21 geared to the shaft first

mentioned, as is well known in this type of machine, these arms being at different elevations and striking a pattern disk 22, the stem of which is mounted to move vertically in the fixed ring of the machine under the control of pattern mechanism which moves the disk to the plane of rotation of first one of the arms and then the other for the adjustment of the advancing cam. There is but a single set of cams in the dial.

The cams for the cylinder needles, shown in Fig. 3, comprise an advancing cam *a*, and a stitch cam *b* for the main feed, and a cam *c* and cam *d* serving as clearing course cams, when the cylinder needles are to be cleared of their stitches, and as advancing and stitch cams for the additional feed when this is thrown in. The means for operating these cams will be described later.

20 The figure (3) shows the relation of the main and additional feeds and the clamp and cutter for the latter, to the said cams, and Fig. 1 shows the relation of the feeds to the single set of cams in the dial.

25 The cam box or cylinder moves in the direction of the arrow *X* in Figs. 1 and 3, and therefore the needles in effect move along the cam path in the direction of the arrow *y*.

30 With the cams in the position shown, and with the dial cams in normal position of Fig. 1, plain rib fabric will be produced, the thread being taken from the single main thread guide 1 while the additional thread 35 for the outside welt of the tubular welt is held out of action by its guide 2, and with its end clamped at 10.

Having completed the rib fabric and having, if desired, thrown in a loose course by 40 depressing the stitch cam *b* of the cylinder, the first action that takes place is the throwing inwardly or retracting of the pivoted cam 13 of the dial to allow the dial needles to simply hold their loops while the cylinder 45 needles knit, say, two courses of welt fabric to prevent the work from raveling back when the clearing course is thrown in. After this the wing cam, if such be used, or the pivoted cam 13 is thrown outwardly to 50 normal position for advancing the dial needles for taking the yarn again. During these actions the cam *c* is inactive.

After the cylinder welt courses have been 55 knitted and the dial cam is restored to normal position as just mentioned, the cam *c* is raised from its inactive position shown in full lines, Fig. 3, to that shown in dotted lines.

The cylinder needles are now advanced by 60 this cam so that their loops get back to their latches, and as no thread is fed at this point (the thread guide 2 for the additional thread being held up), the cylinder needles, when retracted by the cam *d*, will shed their loops 65 to form the clearing course. The cam *d* in

the position shown in full lines is low enough to shed the loops for this clearing or dividing course. The cylinder needles are now empty on this revolution of the cams until they are operated by the cam *a*, when 70 they advance and take thread from the main carrier at 1. The dial needles also take the thread from the carrier 1 at this time. Not having any old loops, however, no stitches are produced by the cylinder needles when 75 they are lowered by the stitch cam *b*, but they simply hold this main thread to form the dividing course, said main thread also serving as a foundation for the welt when the additional thread is thrown in. The 80 cylinder needles having received this foundation thread, they are next acted on by the cam *c* at the next revolution of the machine, and the cam *d*, the guide 2 of the additional thread, however, having first been thrown 85 down to present the additional thread to the cylinder needles which advance to take it by the action of the cam *c* which has already been advanced, as described. The needles then are immediately lowered by the cam *d*, 90 thus forming stitches at this point in the circuit of the machine, where there is no corresponding stitch and retracting cams in the dial so that plain fabric to form the outer 95 wall of the welt will be formed here on the cylinder needles.

Before the cylinder needles again arrive at, or rather before being acted on again by the cam *a* in this revolution of the machine, and after the action above described has 100 taken place of taking thread from the additional feeder to form the outer wall of the welt, the said cam *a* is lowered and the cylinder needles are prevented from taking thread from the main thread guides and 105 therefore at this feed only the dial needles will take the thread, thus producing the inner wall of the tubular welt on this side of the machine, while the outer wall of said welt will be produced at the opposite side of 110 the machine at the additional thread guide and upon the cylinder needles.

It will be seen from the above that the cams *c* and *d* serve a two-fold purpose, in that they advance and retract the needles of 115 the cylinder to clear them and make them ready to receive the foundation thread for forming the outer welt wall, and they also serve as advancing and retracting cams for the formation of the stitches on the cylinder 120 needle in said wall. With the cam *d* in the position shown in full lines, the cylinder needles are retracted far enough to cast off their stitches for the clearing course. When, however, the additional thread is 125 thrown in, the cam *d* is simultaneously lowered to draw sufficient yarn to make stitches. This lowering of the cam *d* at the time the additional thread is thrown into the cylinder needles is effected by a cam 7* on the shaft 130

of the additional thread feeder acting on a lever 23 connected with the rock shaft 24 mounted on the frame or bracket of the additional thread feeder, said shaft having an arm 24' overlying the stem of the cam *d* so that it will press the same down at the time the additional thread is thrown in to draw enough yarn to form a stitch. This cam post, as also the posts of the cams *c*, *a*, *b*, are spring pressed, the springs of *c* and *a* pressing the cams down, while the springs of cams *d* and *b* press them upwardly. When the tubular welt is to be terminated and rib knitting resumed, the first action that takes place is the dropping of the cam *c* out of action and at the point where the last cylinder needle that has cleared its latch passes the additional thread guide 2, said thread is withdrawn by the raising of the guide and the thread is cut and clamped. The advancing cam *a* being now raised from its inactive position, the cylinder needles take the thread from the main thread guide 1, and rib knitting starts from this point.

25 Any desired number of courses can be knit when the machine is making the outer and inner walls of the welt, these being formed independently, the outer wall on the cylinder needles and the inner wall on the dial needles.

30 needies. It will be observed that after the cam *c* is raised for clearing, it remains up to serve as an advancing cam for the cylinder-needles during the formation of the outer wall of
35 the welt thereon. The cam *c* is operated by a cam disk 24* acting on an arm or pin 25 extending from the post *c** of the cam *c*, the said cam disk being fixed to a hollow shaft 26, which is operated to lift the pin 25 and
40 post *c* by an arm 27 striking and being moved by the pattern disk, said arm being on a shaft geared to the hollow shaft 26, and the cam being turned the other way to remove its incline or cam surface from beneath the pin by an arm 28 fixed to the hollow shaft striking the pattern disk 22. The
45 stitch cam *b* is operated for the slack or loose course by an arm 29 fixed to the shaft 30 which passes down through the hollow
50 shaft 26, and has on its lower end a projection 31 entering a notch 32 in a ring 33 which encircles the knitting head and on the other side of the machine is operated from the arms 34, 35, on a shaft 36, and the re-
55 turn arm 37 on a shaft 38 geared to the shaft 36, the shaft 38 having a projection 40 entering a recess in the ring, the arms 34, 35 and 37 being arranged to be struck and operated by the pattern disk 22 when the same is lift-
60 ed into the plane thereof by the pattern mechanism. The arm 29 has studs to bear on inclines on a plate 41 secured to the post *b** of the cam *b*, to press the said cam downwardly to different positions for the loose
65 and slack course.

The cam a is operated in a manner similar to that disclosed in the application of Wildman and Ballard above described to give the cam a step by step downward movement. The post a' of said cam has a pin 42 bearing on the incline 43 of a cam disk 44 on a shaft 45 which has an arm 46 to be operated by contact with the pattern disk 22, and when so struck the cam or incline is removed from under the pin and the cam post moves down under the action of its spring and until it is caught by a catch lever 47 which engages a notch 52, Fig. 7, in the side of the post. This effects the first step in the downward movement of the cam, and the second step is effected by the arm 48 of the catch lever striking the disk 22 and moving it into the position shown, *i. e.* to release the post a' and allow the spring thereof to force it all the way down. This catch lever is pressed by a spring 49. The shaft of the cam disk 44 is geared to a shaft 50 of an arm 51 in a lower plane than the arm 46 and this, when it strikes the disk 22 (the latter having been adjusted to the proper height), will turn the cam disk 44 and raise the cam post a' and the cam a . The post has a notch as at 52, Fig. 7, with a beveled wall. The catch 47 engages this to hold the cam a in its intermediate position. When the post is raised from its low position the catch will move into the notch, but because of the incline the post can move on up to its high position.

Reverting to the thread cutting and clamping means: the cutter comprises the fixed blade 9 and a movable blade 9' pivoted at 9^a to a bracket 9^b. The movable blade is pressed open by a spring 9^c, and it is closed to sever the yarn by a rod 9^d slidably mounted in the frame of the thread feeder, and acted on by the lever or arm y' pivoted to the frame of the feed attachment 9^e, its free end being in position to be operated by contact with the pin 11 which is raised and lowered by pattern mechanism. When the arm y' is swung inwardly by striking the pin, the shear blade 9' will operate in conjunction with the fixed blade to sever the yarn, and the clamping blade 10 which moves with the blade 9' will engage and clamp the yarn upon the upper surface of the fixed blade over which the clamping plate moves it, projecting, as shown in Fig. 6, slightly beyond the edge of the movable blade. This clamping plate is held by a pin 53 to the movable blade of the cutter to move therewith, but it is formed of a thin plate, and being held down on the shear blade by the spring 9^c, it will properly perform its clamping function. When the rod 9^d is moved inwardly and the shear and clamp closed to cut and hold the thread, the said parts will be held in this position by the frictional engagement of a detent lever 54 piv-

oted to the frame and pressed by a spring 55, this spring being sufficient to overcome the tendency of the spring 9^a to open the shear blade and clamp. When, however, the 5 thread guide arm 2 is thrown down to introduce the additional thread to the cylinder needles, the detent lever 54 will be operated by one of the pins 56 on the end of the cam shaft which controls the guide arm 2, and the lever 23—24^a, and said detent lever will 10 release the rod 9^a and the shears and clamp will then be opened and the thread now taken by the cylinder needles.

The additional thread 2^a passes under a 15 guide finger 57, and thence to the guide arm 2, and by this the necessary amount of slack 20 is provided.

We have described various above features 25 as examples of what may be employed in carrying out our invention. Some of these features we do not claim herein; some may be altered and still come within the scope of our invention as defined by the scope of the appended claims.

It will be observed that by throwing the 30 additional thread into the cylinder needles a striping effect on the fabric may be secured because the outside wall of the welt may be knit in any desired color or material.

We claim as our invention:—

1. In combination with a circular knitting machine, a main thread feed, an arm swinging in a plane substantially radially of the machine and having a guide for an additional thread at its free inner end, a cam shaft for operating the said arm, a thread clamp, and cutter means, tappet means for operating the said clamp and cutter to sever and clamp the thread, means controlling the 35 clamp and cutter, said means being in turn controlled from said cam shaft, a needle cam, and means for depressing the needle cam when the additional thread is presented to the needles, said means being operated 40 from the cam shaft, substantially as described.

2. In combination with a circular knitting machine, a main thread feed, a pivotally mounted arm serving as an additional thread feed, a cam shaft for operating the said arm, a thread cutter and clamp, means for operating the cutter to sever the thread and setting the clamp to hold it, a detent device for holding the clamp in set position, said detent device being operated from the cam shaft to release the clamp when the thread feed arm is moved to the needles to supply the additional thread, an arm for depressing one of the needle cams when the additional thread is thrown in, and a connection between said arm and the cam shaft for operating the needle cam when the additional thread is introduced.

3. In combination with a circular knitting machine, a main thread feed, a pivotally mounted arm serving as an additional thread feed, a cam shaft for operating the said arm, a thread cutter and clamp, means for operating the cutter to sever the thread and setting the clamp to hold it, a detent device for holding the clamp in set position, said detent device being operated from the cam shaft to release the clamp when the thread feed arm is moved to the needles to supply the additional thread, an arm for depressing one of the needle cams when the additional thread is thrown in, and a connection between said arm and the cam shaft for operating the needle cam when the additional thread is introduced, said connection including a rock shaft arranged parallel with the cam shaft and having an arm extending therefrom to be operated by the cam shaft, substantially as described.

In testimony whereof, we affix our signatures in presence of two witnesses.
